(57) **CLAIM**

I claim the ornamental design for a combined tray for food and a personal electronic device, as shown and described.

DESCRIPTION

FIG. 1 is a top perspective view of a combined tray for food and a personal electronic device, showing my new design with an outer cover in a closed configuration;

FIG. 2 is a bottom perspective view thereof;

FIG. 3 is a top perspective view thereof, illustrated with the outer cover in an open position and an inner cover in a closed position;

FIG. 4 is a top perspective view thereof, illustrate with the outer cover in the open position and the internal cover in an open position;

FIG. 5 is a top plan view thereof;

FIG. 6 is a bottom plan view thereof;

FIG. 7 is a left-side elevation view thereof;

FIG. 8 is a right-side elevation view thereof;

FIG. 9 is a rear elevation view thereof; and,

FIG. 10 is a front elevation view thereof.

The broken lines showing a personal electronic device in FIGS. 3 and 4 depict unclaimed environmental matter and form no part of the claimed design.
